ELMER L. SCHUMACHER, OF SOUTHBIDGE, MASSACHUSETTS, ASSIGNOR TO AMERICAN OPTICAL COMPANY, OF SOUTHBIDGE, MASSACHUSETTS, A VOLUNTARY ASSOCIATION OF MASSACHUSETTS

OPHTHALMIC MOUNTING

Application filed February 1, 1930. Serial No. 425,240.

This invention relates to improvements in ophthalmic mountings and has particular reference to an improved bridge securing means between the lens holding members of a protection mounting.

The principal object of the invention is to provide means for securely attaching and, at the same time, easily removing the bridge in an ophthalmic mounting and particularly in a goggle or eye protector where an adjustable or flexible type of bridging member is used.

Another object of the invention is to provide means of locking the removable bridge in place so that there will be no opportunity for it to slip or loosen while the mounting is in use.

Another object of the invention is to make possible the ready removal of soiled and worn bridge covering members and their replacement by new ones without the use of special tools.

Another object of the invention is to provide improved means for holding the bridging member out of contact with the face of the wearer.

Another object of the invention is to provide a quick and simple means of adjusting the distance between the lens holding members in such a mounting.

Another object of the invention is to provide improved adjustable means for adjusting the distance between the lens holding members wherein the said distance will remain fixed during the use of the mounting.

Other objects and advantages of the invention will become apparent from the following description taken in connection with the accompanying drawing, and it will be apparent that many changes may be made in the details of construction and arrangement of parts without departing from the spirit of the invention as expressed in the accompanying claims. I, therefore, do not wish to be limited to the exact details shown and described as the preferred forms only have been shown by way of illustration.

Referring to the drawing:

Fig. I is a front elevation of the protection mounting embodying the invention.

Fig. II is a side elevation of the protection mounting shown in Fig. I.

Fig. III is a fragmentary perspective view showing the flexible bridge connection to the protection mounting.

Fig. IV is a sectional view taken as on line IV—IV of Fig. III of a slight modification of the invention.

In most types of eye protectors used in industrial occupations by welders, chippers and others, the eyecups are connected centrally by a flexible member, such as a chain, which permits a close contact between the edge of the eyecup and the wearer's face and also permits the goggles to be folded when not in use. These chain bridges are often covered with a rubber tube, or a similar protective member which prevents the chain from becoming rusted and discolored from perspiration and the like. It is also a feature of these bridges that adjustment of the distance between the eyecups is usually made by twisting one eyecup and so shortening the chain.

The undesirable feature of this adjustment is its impermanency and undue strain on the covering member from the unnatural position of the chain inside. When one eyecup member is released, the chain member untwists and the adjustment is thereby lost and must be repeated when the goggle is again brought into use.

As the chain is invariably permanently fixed to the eyecup at each end and not removable without a great deal of labor and damage to the eyecup, it will readily be seen that the protective covering will soon become soiled and unsanitary and that no means are provided for changing it.

It is the prime object of my invention, therefore, to provide a simple means whereby the distance between the eyecup may be permanently adjusted and the protective member on the bridging means quickly and easily interchanged.

Referring to the drawing, in which similar characters of reference designate similar parts throughout several views, the device embodying the invention comprises a pair of eyecups 1 having a face engaging bead 2 at one end thereof and a beveled groove 3 at the opposite end thereof for holding the lens 4.

in the eyecup. The eyecups 1 are split at 5 on the nasal side to permit expansion for the insertion and removal of the lens 4. Adjacent the split 5 and secured to the opposite ends of the expansible eyecup 1 is a pair of lug members 6 through which a screw 7 extends to secure the lens 4 in the eyecup. One of said lugs is provided with a pin 8 which extends through a perforation formed in the opposite lug 6 to provide means for the attachment of the end link of a chain member 9 which extends between and secures the eyecups together. The chain member 9 is provided with a protective resilient covering 10 formed from a rubber tube or similar means to guard against rusting and discoloring from perspiration and the like. The mounting is held on the face of the wearer by a suitable headband or the like 11.

20 In the operation of the device the screw 7 is loosened to permit the pin 8 to be drawn clear of the perforated lug 6. The chain 9 may then be removed from the pin 8 to permit the removal of the tubular member 10 to 25 allow it to be replaced with a new one. The distance between the eyecups may be shortened and adjusted to the face of the wearer by either removing links or hooking the second or third link instead of the end one on to 30 the pin member 8. This forms a ready means of adjustment and is quite permanent for any wearer as distinct from the prior art method of twisting one eyecup which was obviously a very transitory adjustment and lost as soon as the mounting was removed from the wearer's face.

The chain member 9 being easily removable makes it a simple matter to change the rubber tubing 10 when soiled or worn and so adds to 40 the cleanliness of the goggle and prevents rusting of the metal chain which would take place were a worn tubular covering to be used as was inevitable in the prior art.

A slight modification is shown in Fig. IV in 45 which instead of the pin 8 there is used a screw member 12. The object of the use of the screw is to permit the interchanging of the tubular member 10 and adjustment of the distance between the eyecup without the necessity of 50 loosening the lens from its position in the eyecup as is necessary with the construction shown in Fig. III. To detach the chain 9 from the eyecup 1 in the construction shown in Fig. IV it is only necessary to remove 55 the screw 12. This does not disturb the screw 7 which holds the lens 4 against displacement in the eyecup 1. The screw member 12 is threaded to its supporting lug and is adapted to extend through an opening 13 formed 60 in the opposite lug 6. This permits the lens 4 to be removed from the eyecup 1 without having to loosen the screw 12.

The edge 4, which is adapted to contact with the face of the wearer and be shaped to 65 conform to the wearer's face, may be provided

with a protective covering such as rubber or leather, or some similar means.

From the foregoing it will be seen that I have provided a simple yet ingenious means for carrying out the object of the invention, particularly in providing extremely simple and efficient detachable means for the bridging member of an ophthalmic mounting of the type described without the danger of the bridging member becoming loosened while the mounting is in use.

Having described my invention, I claim:

1. In a device of the character described, a pair of eyecups each having split ends on their nasal sides and each split end having a projecting lug portion adjacent the split so positioned as to leave a space between the lugs when the split ends engage each other, a bridge member having a plurality of openings therein spaced longitudinally from each other, a portion of the bridge extending into the spaces between the lugs so that an opening of the bridge occupies a position between each set of lugs, means securing each set of lugs together exteriorly of said openings and means extending through each set of lugs and through the respective openings in the bridge member.

2. In a device of the character described, a pair of eyecups each having split ends on their nasal sides and each split end having a projecting lug portion adjacent the split so positioned as to leave a space between the lugs when the split ends engage each other, a bridge member having a plurality of openings therein spaced longitudinally from each other, a portion of the bridge extending into the spaces between the lugs so that an opening of the bridge occupies a position between each set of lugs, screw means securing each set of lugs together exteriorly of said openings and screw means extending through each set of lugs and through the respective openings in the bridge member.

3. In a device of the character described, a pair of eyecups each having split ends on their nasal sides and each split end having a projecting lug portion adjacent the split so positioned as to leave a space between the lugs when the split ends engage each other, a bridge member having a plurality of openings therein spaced longitudinally from each other, a portion of the bridge extending into the spaces between the lugs so that an opening of the bridge occupies a position between each set of lugs, screw means securing each set of lugs together exteriorly of said openings and a pin member secured in one lug and extending into the other lug and through the respective openings in the bridge member.

ELMER L. SCHUMACHER.
